UNITED STATES PATENT OFFICE.

CHARLES H. HAESELER, OF PHILADELPHIA, PENNSYLVANIA.

PNEUMATIC TOOL.

1,297,679.

Specification of Letters Patent. Patented Mar. 18, 1919.

Application filed March 11, 1916. Serial No. 83,470.

To all whom it may concern:

Be it known that I, CHARLES H. HAESELER, a citizen of the United States, residing in the city and county of Philadelphia, State 5 of Pennsylvania, have invented a new and useful Pneumatic Tool, of which the following is a specification.

My present invention relates to a novel construction of a pneumatic tool and more 10 particularly to a pneumatic tool in which a reciprocating piston is employed to impact against the working tool.

My invention consists in its broad and generic scope of a novel pneumatic tool, where- 15 in the handle and the cylinder or piston cas- ing are constructed in a novel manner, whereby they can be readily assembled and securely locked in assembled position, and wherein they may be readily taken apart 20 when occasion requires it.

It further consists of a novel construction of handle having a tapered recess or cham- 25 ber in its body portion, and a novel construc- tion of a cylinder or casing having a ta- pered portion to engage the walls of the re- cess or chamber in the handle.

It further consists of novel means for 30 locking the handle and casing in assembled position.

Other novel features of construction and 35 advantage will hereinafter more clearly ap- 40 pear in the detailed description of my in- vention.

For the purpose of illustrating my inven- 45 tion, I have shown herein, a typical embodiment 50 thereof which well illustrates the prin- ciples of the invention, but it is of course to be understood that this embodiment is typi- 55 cal only and that the various instrumental- 60 ties of which my invention consists can be variously arranged and organized and that my invention is not limited to the precise 65 arrangement and organization of these in- strumentalities as herein shown and de- 70 scribed.

Figure 1 represents a longitudinal section 75 of a pneumatic tool embodying my inven- 80 tion.

Fig. 2 represents a section on line $x-x$ 85 of Fig. 1.

Fig. 3 represents a section on line $y-y$ 90 of Fig. 1.

Fig. 4 represents a section on line $z-z$ 95 of Fig. 8.

Fig. 5 represents a side elevation of a 100 locking bolt.

Fig. 6 represents a side elevation of a re- 105 pair locking bolt.

Fig. 7 represents a sectional view of a part 110 of the cylinder, showing more particularly 60 the threaded portion for receiving the lock- 65 ing bolt.

Fig. 8, represents, on an enlarged scale, a 120 sectional elevation of the handle and a por- 65 tion of the cylinder.

Similar numerals of reference indicate 125 corresponding parts in the figures.

Referring to the drawings:

My present invention is especially adapted 130 to be employed in pneumatic tools provided 70 with a reciprocating piston and with a dis- 135 tribution valve controlling the reciproca- 75 tion of the piston and located in the handle in a chamber separate and distinct from the cyl- 80 inder in which the piston reciprocates. Any 85 desired type of distribution valve may be 80 employed and any desired type of throttle 90 valve mechanism may be employed to control 95 the introduction of motive fluid to the dis- 95 tribution valve.

As my present invention is particularly 100 directed to the construction of the co-oper- 105 ating portions of the handle and cylinder, I 110 will first describe such parts.

1 designates the handle of a pneumatic 115 tool embodying my invention, said handle 85 being provided with the grasping portion 2 and with a sleeve 3, which is recessed to form 90 a tapered socket 4 which extends throughout 95 the greater part of the length of the sleeve 100 3. 5 designates the barrel or casing, the in- 105 ner end of which is provided with a tapered 110 portion 6, which is accurately machined to 115 fit the corresponding tapered portion 4 in 120 the handle, and the tapered portion 6 is of 125 slightly less length than the tapered socket 130 4 in order to provide a space 7 between the 135 ends of the tapered parts, so that any wear 140 which may occur on the tapered parts, due 145 to their being separated from each other, for 150 repairs to the cylinder or piston or other 155 causes, will be taken up. The cylinder 5 is 160 provided with a piston chamber 8 in which 165 reciprocates a piston 9, which during its 170 movement uncovers the ports 10 which com- 175 municate with exhaust passages 11, which 180 latter communicate with the atmosphere 185 through exhaust ports 12. The passages 11 190 are drilled from the rear end of the cylinder 195 and are screw threaded for a portion of their 200 length, as indicated at 13.

The rear end of the sleeve 3 of the handle

1 has holes 14 drilled through it, which are adapted to register with the passages 11 in the cylinder 5. 15 designates bolts adapted to pass through the holes 14 and the passages 5 11 and these bolts are provided with threaded ends to engage the corresponding threads 13 in the passages 11, and these bolts are prevented from unscrewing by means of lock washers 16, which consists of split rings, 10 as will be apparent from Figs. 1 and 8. The passages 11 are screw threaded for a greater length than the length of the threaded portion of the locking bolt 15, in order that longer locking bolts 17 may be employed 15 in case the threads 13 should become worn or stripped by frequent removal of the locking bolt 15 or by undue strain placed upon them in tightening the handle with respect to the cylinder. In order to remove 20 the handle, the locking bolts 15 are unscrewed and the piston 9 is pushed to the rear end of the piston chamber 8 until it abuts against the rear wall of the recess or chamber in the handle. A striking bar or 25 rod is inserted through the forward end 18 of the cylinder, and through the opening 19, until it abuts against the forward end of the piston 9, so that the handle can be disengaged from the cylinder.

30 In the operation of the pneumatic tool, it will be understood by those skilled in the art that motive fluid enters through the inlet 20, passing by the throttle valve 21, and through the passage 22, into the chamber 23, thence through ports 24 into the valve chamber 25, and from the valve chamber 25 through port 26 into the recess 27 in the cylinder 5 in rear of the piston 9, causing the same to move forwardly and impact against the working tool. As soon as the piston passes the ports 10, a slight compression of motive fluid at the forward end of the cylinder acting through the passage 28 and ports 29 causes the distribution valve 30 to be moved into the position seen in Fig. 8, whereupon live motive fluid passes through the port 31 into the valve chamber 25 and therefrom through port 29 and passage 28 in front of the shoulder on 40 the piston 9 and causes the same to be returned to its rear or initial position. The exhaust of motive fluid takes place through the ports 10 and 12 and passages 11.

45 It will be apparent from the foregoing 55 that in accordance with my present invention, the coöperating parts of the cylinder and handle are provided with tapered portions in frictional engagement with each other, and means are provided to lock the 60 parts in their assembled position. My present invention is not confined to the particular type of pneumatic tool illustrated, but may be employed, as is apparent, in conjunction with other types of pneumatic 65 tools of either the valve or valveless type,

wherein the handle and cylinder form separate parts.

In devices of this character, when employed for riveting, the barrel or cylinder of the tool is held by the left hand of the 70 operator and if the exhaust port or ports are located at the central portion of the barrel it interferes with the proper handling of the tool and such ports would be liable to be covered by the hand of the operator. 75 By utilizing the open end of a passage for the fastening bolt, one is enabled to reduce to a minimum the number of passages in the cylinder of the tool and thereby eliminate the weakening of the cylinder which would 80 otherwise follow.

It will also be apparent that my present invention is designed to be employed in conjunction with pneumatic hammers, wherein in the stroke of the piston is greater or less 85 than its own length. I have preferred to illustrate the rear end of the cylinder as having a conical contour to coöperate with the corresponding conical contour of the wall in the chamber of the body portion or 90 sleeve of the handle, but it will be apparent that other forms of tapers will be employed and still be within the spirit and scope of my invention.

It will now be apparent that I have devised 95 a novel and useful pneumatic tool, which embodies the features of advantage enumerated as desirable in the statement of the invention and the above description, and while I have, in the present instance, shown and described a preferred embodiment thereof which will give in practice satisfactory and reliable results, it is to be understood that the same is susceptible of modification in various particulars without departing from the spirit or scope of the invention or sacrificing any of its advantages. 100

Having thus described my invention, what I claim as new and desire to secure by Letters Patent, is:—

1. In a pneumatic tool, a handle having a sleeve forming a tapered socket, a cylinder having a tapered end to frictionally engage said socket and having exhaust passages extending in proximity to the rear end of the cylinder, and means engaging the handle and interlocking with the walls of said passages to maintain the handle and cylinder in assembled position.

2. In a pneumatic tool, a handle having a tapered socket, a cylinder having a tapered end to frictionally engage said socket and having exhaust passages extending in proximity to the end of the cylinder, and provided with a threaded portion, and bolts passing through said handle and into said passages and having threaded ends to engage the threaded portions of said passages.

3. In a pneumatic tool adapted to be manually supported, a handle having a grasping

portion and provided with a sleeve forming a tapered socket, a cylinder having a tapered end to frictionally engage said socket and having exhaust passages extending in proximity to the end of the cylinder, and provided with a threaded portion, bolts passing through said handle and into said passages and having threaded ends to engage the threaded portions of said passages, and means to prevent movement of said bolts.

4. In a pneumatic tool, a handle having a tapered socket, a cylinder having a tapered end to fit said socket and having a piston chamber with exhaust passages therefrom opening through the side wall of the cylinder, said passages extending in proximity to the rear end of the cylinder, bolts passing through said handle, closing the outer ends of said passages, and interlocking with the walls thereof, and a piston in said piston chamber, and said cylinder having its forward end open, whereby a tool may be inserted through such end to move the piston against the handle and disengage the handle from the cylinder.

5. In a portable pneumatic tool adapted to be manually supported, a handle having a grasping portion adapted to be manually held and provided with a sleeve whose rear end is closed by a portion integral therewith, said sleeve having an internal, tapered, conical, unthreaded socket, the wall of the latter diverging from said integral portion forwardly to the outer end of said sleeve, a piston cylinder provided with a piston chamber 35 and having its rear end tapered to frictionally engage said socket of said handle sleeve to form therewith a tapered joint, valve mechanism contained in said sleeve, and ports controlled by said valve mechanism 40 and extending through said tapered joint for the introduction and exhaust of motive fluid to opposite ends of said piston chamber.

6. In a portable pneumatic tool adapted to be manually held, a handle comprising an integral member provided with a grasping portion to be manually held and closed at its rear end and a sleeve open only at its forward end and having an internal, tapered, unthreaded, conical socket, whose greatest 50 diameter is at its forward end, a cylinder having its rear end unthreaded and tapered to conform to the taper of said socket to frictionally engage the latter and form therewith a tapered joint, a piston in said cylinder, valve mechanism contained in said handle sleeve, ports through said tapered joint common to said valve mechanism and cylinder and controlled by said valve mechanism 55 to alternately introduce motive fluid to opposite ends of said cylinder to effect the reciprocations of said piston, and fastening devices common to said handle and cylinder for locking them in frictional engagement.
